UNITED STATES PATENT OFFICE.

HILARIUS PATTBERG AND ADOLPH GÄRTNER, OF JERSEY CITY, NEW JERSEY,
ASSIGNORS TO LEWIS PATTBERG, HILARIUS PATTBERG, AND PHILIPP
PATTBERG, OF NEW YORK, N. Y.

ALBUM-STAND.

SPECIFICATION forming part of Letters Patent No. 269,702, dated December 26, 1882.

Application filed September 2, 1882. (No model.)

To all whom it may concern:

Be it known that we, HILARIUS PATTBERG and ADOLPH GÄRTNER, of Jersey City Heights, Hudson county, New Jersey, have invented an Improved Album-Stand, of which the following is a specification.

Figure 1 represents a vertical cross section of our improved album-stand. Fig. 2 is a perspective view of a book supported on said stand. Figs. 3 and 4 are side views of the same.

The object of this invention is to produce a stand for holding albums or other books in convenient position for inspection of their contents.

The invention consists principally in combining with the frame that supports the album or book pivoted arms, which join said frame to the covers of the book, and longitudinal supports for resting the covers thereon, all as hereinafter more fully described.

In the accompanying drawings, the letter A represents the base of our improved album-stand, in which base is suitably swiveled a vertical post, B, which can be revolved around its axis in a socket provided for its reception in the said base A. This socket is by preference a vertical tube, a, as shown in Fig. 1. In the upper part of the post B is hung by a horizontal pivot-pin, b, the downwardly-projecting lip d of the book-holding frame D. This lip d is rigidly connected with the frame D, and, projecting downward therefrom, is clamped between upwardly-projecting ears e of the post B.

For clamping purposes, a nut on the pin b may be employed, or the pin b may be threaded to screw into one of the ears e for the like purpose. On the lip d or any other part of the frame D are downwardly-projecting lugs f and

g, which are in such a position that they can come in contact with the post B. Thus Fig. 3 shows the frame D to be in a horizontal position when the lug g strikes the post, and Fig. 4 shows the frame D to be in an inclined position when the lug f strikes the post. The frame D can therefore be held in either of the said positions or in any intermediate position. The frame proper, D, consists, in the example

shown, of a central bar, h, having transverse brackets or cross-pieces i i near its ends, which 50 brackets serve to support two outer bars, j j, parallel to the bar h, or nearly so. In the brackets i are also held, somewhat nearer to the bar h than the bars j, two rods, k, to which are hinged folding arms E E, there being two 55 arms E on each rod k. These arms E are of suitable length, and are slotted near their outer ends, as shown in Figs. 3 and 4, and are adapted to be fastened to the covers F of the book by suitable thumb-screws, l. The book has a clasp, 60 G, of suitable construction.

When the book is to be placed on the stand it is laid with its back upon the frame D. The arms E E are then brought against the covers of the book and secured thereto by the thumb-screws l. When the clasp G closes the book it will be in the position shown by full lines in Fig. 1; but when the clasp G is unfastened the book can be thrown open, as shown by dotted lines in Fig. 1, the slots in the arms E allowing 70 the free movement of the covers F in opening and closing the book. When the book is open the covers F and arms E rest upon the two rods j j. The leaves of the book can in this position be turned from one side to the other to 75 allow full and free inspection of all its contents. At the same time the book may be tilted into the position shown in Fig. 4, whether open or shut, or may be inspected when the frame D is horizontally placed, as in Fig. 3. 80 At any event this invention provides a convenient support for photographic albums, large pictorial works, bibles, &c., whose contents may be readily examined by one or more persons, where its displacement and its manipulations will not be apt to injure the table on 85 which it is placed or the book itself.

Suitable blocks or cushions, m, may be applied to the arms E where they are to rest on the rods j, as shown in Fig. 1. 90

Where the book has no clasp, a suitable clasp may be applied to the arms E E to enable them to hold the book in the closed position, or, in lieu of such clasp, binding-screws for holding the arms E in an upright position could readily 95 be applied.

We claim—

1. The combination of the post B with the pivoted frame D, pivots *k*, book-embracing arms E, and bars *j j*, which are rigidly affixed 5 to frame D and parallel to the pivots *k*, substantially as described.
2. The combination of the base A and post B with the pivoted lip *d*, having lugs *f* and *g*, and with the frame D and arms E E, substantially as specified.
3. The frame D, constructed of the bar *h*, cross bars *i*, bars *j k*, pivoted arms E, and lip *d*, in combination with a supporting-post, and

with the fasteners *l* for connecting it to the covers of a book, substantially as herein shown 15 and described.

4. The frame D, having the slotted folding arms E E, and carrying rigidly-secured rests *j j* and pivots *k*, in combination with the pins *b* and clasp G, substantially as herein shown and 20 described.

HILARIUS PATTBERG.
ADOLPH GÄRTNER.
